(57) **ABSTRACT**

In the roof window (1), each sash member (31, 32) comprises a profile element (31a, 32a), an inner element (32c) and an intermediate element (31b, 32b) forming a connection between the profile element and the inner element of each sash member in an assembled condition of the sash (3). The profile elements (31a, 32a) of the sash members (31, 32) are located along respective exterior edge portions of the pane (4) in the assembled condition of the sash (3), and the profile elements (31a, 32a) of the top sash member (31) and the two side sash members (32) are formed as a set of longitudinal profiles of substantially uniform cross-section.

**ROOF WINDOW COMPRISING A SASH
WITH PROFILE ELEMENTS AND METHOD
OF MANUFACTURING A ROOF WINDOW**

TECHNICAL FIELD

The present invention relates to a roof window comprising a frame, a sash, and a pane, in which the frame comprises a set of frame members including a top frame member, two side frame members and a bottom frame member and the sash comprises a set of sash members including a top sash member, two side sash members and a bottom sash member, each frame and sash member defining a longitudinal direction, and the pane comprises a number of edge portions and an exterior pane surface defining a plane of the roof window in an assembled condition of the roof window. The invention furthermore relates to a method of manufacturing such a roof window.

BACKGROUND ART

Roof windows to be installed in inclined roof surfaces come in a variety of types. When selecting a roof window type for a specific installation location in a building, parameters such as operability, thermal properties, weather-tightness, and suitable finishing to the interior of the building are typically given substantial weight; however, it is also often desired and in some areas in fact necessary to factor in the external appearance as well. This applies in particular when installing roof windows in conservation areas, in which building regulations may demand that the roof windows meet standard or local requirements. Thus, certain requirements apply depending on whether the installation concerns a newly fitted roof window, or to replace an existing window or rooflight as part of a renovation or refurbishment project.

The windows or rooflights of past times were typically made of cast iron with single glass pane pieces, separated by one or more cast iron glazing bars, and the thermal efficiency of these roof windows or rooflights left room for improvement. To fulfil the energy performance required by modern day building regulations, conservation roof windows are typically provided with an insulating pane, while at the same time setting out to mimic the look of traditional rooflights.

In many installation situations it is a further requirement that the conservation roof window is able to be installed with a "low profile", i.e. that the height of the parts of the roof window protruding above the surrounding roofing is as small as possible. This is particularly pronounced in buildings with substantially flat roofing materials, such as slate or shingle. To meet this requirement, most major roof window manufacturers allow installation in at least two levels, thus accommodating the height of various roofing profiles and installation conditions.

With an ever-increasing awareness of environmental considerations and the wish to reduce or even eliminate the climate footprint of products, there is furthermore a need for providing products which are more environmentally friendly in terms of manufacturing, supply, installation, and use.

Taking all of the above requirements into account, it is an ongoing quest to improve a roof window for conservation purposes.

SUMMARY OF INVENTION

With this background, it is an object of the invention to provide a roof window in which in particular the manufac-

2

ture and assembly are facilitated, but which also provide adequate weather-proofing in use.

In a first aspect, this and further objects are achieved with a roof window of the kind mentioned in the introduction 5 which is furthermore characterised in that each sash member comprises a profile element, an inner element and an intermediate element forming a connection between the profile element and the inner element of each sash member in an assembled condition of the sash, that the profile elements of 10 the sash members are located along respective exterior edge portions of the pane in the assembled condition of the sash, and that the profile elements of the top sash member and the two side sash members are formed as a set of longitudinal profiles of substantially uniform cross-section.

15 By this design, the facilitated manufacture and assembly aimed at are achieved in that the longitudinal profiles to form at least the top and side sash members may be manufactured and assembled in a first step of the manufacturing process, and subsequently connected to the intermediate and inner 20 elements. At the same time, the profiles of the sash members may form part of the weather-shielding arrangement of the roof window in use, since they are all present along exterior edge portions of the pane.

In one embodiment, each profile element comprises a 25 head portion and an adjoining outer portion, wherein the head portion is substantially parallel to the plane of the roof window in the assembled condition of the roof window, and wherein the adjoining outer portion is substantially perpendicular to the head portion. These measures provide for a 30 harmonic appearance while at the same time contributing to the weather-shielding performance of the roof window.

In another embodiment, the pane comprises an exterior sheet and at least one interior sheet, and wherein the exterior sheet comprises an extended portion extending beyond a 35 bottom edge portion of the at least one interior sheet to a bottom edge portion of the exterior sheet, the pane having a common side edge portion and a common top edge portion. The provision of a so-called stepped pane not only improves the visual performance of the roof window but also, the 40 drainage of rain and other precipitation from the pane to the roofing below the roof window as seen in the inclination of the roof is facilitated. The bottom frame member remains protected under the extending portion of the exterior sheet of the pane.

45 It is preferred that the head portion of the profile element of each of the top sash member and the two side sash members is located on the exterior side of the exterior pane surface, preferably on the outer side of the side edge portion and the top edge portion of the pane. In this way, rain and 50 other precipitation falling onto the pane will remain within the basin thus formed and be guided downwards in the direction of the inclination of the roof. In addition, these features emphasise the appearance of the roof window to resemble traditionally-styled windows.

55 At the bottom of the roof window, which is less exposed to weathering as compared to the sides and in particular the top, it is preferred that the head portion of the profile element of the bottom sash member is located on the interior side of the extended portion of the exterior sheet of the pane. This 60 makes it possible to utilise the advantages of a stepped pane in full.

In an embodiment, which in particular contributes to the structural integrity of the roof window and which also improves the weather-shielding properties even further, the 65 length of the profile elements of the two side sash members substantially corresponds to or exceeds slightly the distance between the top edge portion of the pane and the bottom

edge portion of the exterior sheet of the pane, such that an overlap is provided between the profile elements of the two side sash members and the profile element of the bottom sash member.

In a further embodiment, the inner elements of the sash members form a coherent inner element sash structure supporting an interior edge portion of the pane in the assembled condition of the sash, the inner elements of the sash members preferably having a substantially identical cross-section. The flexibility in the configuration of the inner elements makes it possible to tailor the inner members according to for instance various interior design lines.

In a presently preferred embodiment, the longitudinal profiles form mitred joints between the profile element of the top sash member and the respective profile element of the side sash members in the assembled condition of the sash. Mitred joints provide for a particularly cost-effective manufacturing and assembly process, since the profile elements may be formed from a single coherent profile, which is cut to form sections intended to constitute one side, the top, and the other side in the assembled sash.

In order to improve the tightness at the corners of the sash members of a roof window according to this preferred embodiment, a corner key may be provided at each mitred joint, preferably supplemented by the application of a sealant, and the corner key may have a generally L-shaped configuration with two perpendicular legs divided by a channel, preferably provided with a set of primary openings, more preferably each leg is adjoined by a depending skirt on a first side, preferably provided with one or more secondary openings. This configuration is particularly advantageous for proper distribution of a suitable sealant such that it is ensured that an area around the joining edges of the mitred joint is entirely covered by the sealing.

Advantageously, each leg is adjoined by an inclined section on a second side, and the channel advantageously ends in a tongue, optionally adjoining an inclined channel section. These measures have shown to improve the sealing properties even further.

In a further embodiment, each of the longitudinal profiles forming the profile elements of the top sash member and the two side sash members comprises an inner portion adjoining the head portion, said inner portion being configured to overlap the pane in the assembled condition of the sash. By this configuration, the draining properties at the pane are improved even further.

In further developments of this embodiment, the head portion of each profile element is configured to protrude to the exterior relative to the exterior surface of the pane in the assembled condition of the sash, and the inner portion is preferably inclined from the head portion relative to the head portion and extends inwards and to the interior, towards the exterior surface of the pane in the assembled condition of the sash. In addition to improving the weather-shielding properties by ensuring appropriate draining of precipitation from the pane to the roofing, this design underpins the appearance of the roof window to resemble a traditionally-styled window.

In a second aspect, a method of manufacturing such a roof window is provided.

Other presently preferred embodiments and further advantages will be apparent from the subsequent detailed description and drawings.

A feature described in relation to one of the aspects may also be incorporated in the other aspect, and the advantage of the feature is applicable to all aspects in which it is incorporated.

BRIEF DESCRIPTION OF DRAWINGS

In the following description embodiments of the invention will be described with reference to the drawings, in which

FIG. 1 is a perspective view of a roof window in an embodiment of the invention, seen from an interior side;

FIG. 2 is a perspective view of the roof window of FIG. 1, seen from an exterior side;

FIG. 3 is a perspective cross-sectional view of a side of a roof window in another embodiment, with a mounting bracket, corresponding to a cross-section along the line III-III in FIG. 2;

FIG. 4 is a view corresponding to FIG. 3, with an insulating frame piece shown exploded;

FIG. 5 is a cross-sectional view along the line III-III in FIG. 2;

FIG. 6 is a cross-sectional view of a roof window in a further embodiment, corresponding to a cross-section along the line VI-VI in FIG. 2;

FIG. 7 is a view corresponding to FIG. 6, with the sash in an open position;

FIG. 8 is a perspective cross-sectional view of a roof window in an embodiment incorporating an operating assembly, corresponding to a cross-section along the line VIII-VIII in FIG. 2;

FIG. 9 is a cross-sectional view along a line parallel to the line VIII-VIII in FIG. 2;

FIG. 10 is a partial perspective view of a roof window incorporating a hinge assembly and an operating assembly, with the sash in an open position;

FIG. 11 is a partial perspective sectional view of the frame of the roof window of FIG. 10, together with an insulating frame;

FIG. 12a is a partial perspective view of the sash of the roof window of FIG. 10;

FIG. 12b is a perspective sectional view of the sash of FIG. 12a;

FIG. 13a is an exploded sectional view of the details of FIG. 12a;

FIG. 13b is a perspective view of a detail of the sash of FIG. 12a;

FIG. 14a is a partially exploded perspective view of the sash of FIG. 12a;

FIG. 14b is a perspective sectional view of details shown in FIG. 13a;

FIG. 15 is a partial perspective view of an intermediate element of the sash of the roof window of FIG. 10;

FIG. 16 is a sectional view corresponding to FIG. 5, but of the sash isolated from the frame;

FIG. 17 is a simplified cross-sectional view corresponding to FIG. 16;

FIG. 18 is a view corresponding to FIG. 17, of a roof window in another embodiment of the invention, in which the pane has a larger total thickness;

FIG. 19 is an exploded perspective view of an upper corner of the sash of a roof window in a further embodiment;

FIGS. 20 and 21 are perspective views, seen from different angles, of a corner key of the sash of FIG. 19;

FIG. 22 is an exploded perspective view of a sash and a frame of a roof window in an embodiment incorporating a hinge assembly;

FIG. 23 is a partial perspective view of details of the roof window of FIG. 22;

FIG. 24 is a perspective view of a roof window in an embodiment of the invention, incorporating a flashing assembly;

5

FIG. 25 is a partial perspective exploded view of an upper corner of the frame of the roof window in the embodiment of FIG. 24;

FIGS. 26 and 27 are cross-sectional views of elements of the interface unit of FIG. 25;

FIG. 28 is a partial side view of a roof window in the open position shown in FIG. 7, showing the interaction between the sash and the interface unit of FIG. 25;

FIG. 29a is a cross-sectional view along the line XXIX-XXIX in FIG. 24;

FIG. 29b is a view corresponding to FIG. 29a, of an alternative embodiment of the general embodiment of FIG. 24;

FIG. 30 is a cross-sectional view of an alternative embodiment, corresponding to a cross-sectional view along the line XXX-XXX of the general embodiment of FIG. 24;

FIG. 31 is a cross-sectional view of an alternative embodiment, corresponding to a cross-sectional view along the line XXXI-XXXI of the general embodiment of FIG. 24;

FIG. 32 is a partial perspective view of the top right-hand corner of the alternative embodiment of the roof window;

FIG. 33 is a partial sectional view of the top right-hand corner of an embodiment of the roof window according to the invention;

FIG. 34 is a partial perspective view of the bottom right-hand corner of the alternative embodiment of the roof window;

FIG. 35 is a perspective view, on a larger scale, of a detail of the embodiment of FIG. 34; and

FIG. 36 is a perspective view, on a larger scale, of a further detail of the embodiment of FIG. 34.

DESCRIPTION OF EMBODIMENTS

In the following detailed description, a preferred embodiment of the present invention will be described. However, it is to be understood that features of the different embodiments are exchangeable between the embodiments and may be combined in different ways, unless anything else is specifically indicated. It may also be noted that, for the sake of clarity, the dimensions of certain components illustrated in the drawings may differ from the corresponding dimensions in real-life implementations.

It is noted that terms such as "up", "down", "left-hand", "right-hand", "exterior", "interior", "outer", "inner" are relative and refers to the viewpoint in question. In general, when referred to an exterior side, this relates to a side of a roof window in the mounted condition facing the outdoors or external side of the building. Conversely, an interior side refers to a side facing the internal side of the building, i.e. typically a subjacent room including any light shaft. Terms such as "outwards" and "inwards" are directions generally perpendicular to an interior-exterior direction, taking as its base point a centre of the roof window.

General Description of a Roof Window—FIGS. 1 and 2

Referring initially to FIGS. 1 and 2, a roof window 1 is shown. The roof window 1 is intended to be installed in an inclined roof surface (not shown).

The roof window 1 comprises a frame 2, a sash 3, and a pane 4. The frame 2 comprises a set of frame members including a top frame member 21, two side frame members 22, 23 and a bottom frame member 24. Correspondingly, the sash 3 comprises a set of sash members including a top sash member 31, two side sash members 32, 33 and a bottom sash member 34. While the frame 2 and sash 3 are described as

6

rectangular structures, some principles of the presented concepts may be applicable to other geometrical shapes as well.

The pane 4 comprises a number of edge portions generally associated to members of the sash 3 as will be described in further detail below. When in a closed position, an exterior pane surface 4e defines a plane of the roof window 1 in an assembled condition of the roof window 1. The assembled condition of the roof window 1 is achieved when main components of the frame 2 and sash 3 have been assembled and the frame 2 and sash 3 are connected to each other, for instance in an installed position when the roof window 1 is ready for use. Correspondingly, an assembled condition of the sash 3 is achieved once main components of the sash 3 have been assembled, and an assembled condition of the frame 2 when main components of the frame 2 are assembled.

An interior pane surface 4i faces the interior, typically a room of a building subjacent the roof surface in which the roof window 1 is installed. A glazing bar 45 is fitted to the exterior surface of the pane 4e, and a glazing bar cover 46 is fitted on the interior pane surface 4i. Although less practical, it would also be possible to have a two-part pane with two pane halves divided by a throughgoing glazing bar. In wide roof windows, it is also possible to have more than one glazing bar, for instance two glazing bars dividing the surface of the pane visible from the exterior into three sections.

In the embodiments shown, the sash 3 is openable relative to the frame 2, to obtain one or more open positions. In such open positions, the sash 3 and pane 4 are moved out of the plane of the roof window 1. As will be described in the following, the sash 3 is shown as being tophung, i.e. during normal use, the sash 3 is rotated about a substantially horizontal hinge axis at or near the top frame member 21 and top sash member 31. It is however conceivable to apply some principles of the presented concepts for roof windows on different types of windows having other opening patterns, or being provided as fixed skylights.

Further details shown in FIGS. 1 and 2 include an operating assembly 5, here shown as a manual handwinder or screwjack. Other operating assemblies may be present as well.

Also shown is a representative mounting bracket 6 forming part of a plurality of mounting brackets forming a load-transferring connection between the roof window 1 and a surrounding roof structure (not shown). Such a roof structure may include rafters and battens, plywood or other construction materials.

Finally, an insulating frame 7 is shown. Insulation by an insulating frame is optional and may be provided along only some of the frame members or as shown surrounding all four frame members 21, 22, 23, 24.

In the following description of various embodiments, elements having the same or analogous function carry the same reference numerals throughout. Suitable variations and modifications will be apparent to the person skilled in the art.

Mounting Bracket and Roof Window with Set of Mounting Brackets—FIGS. 3 to 4

Typically, a roof window such as the roof window 1 shown in FIGS. 1 and 2 is supplied with a set of mounting brackets 6. As indicated, two mounting brackets 6 are fastened to each side frame member 22, 23. In the following, a single mounting bracket 6 will be described, in association

with one side frame member 22. The mounting brackets 6 of the set will most often be identical, although variations are possible.

The mounting bracket 6 comprises a first bracket leg 61 for fastening to the roof structure and a second bracket leg 62 for fastening to the frame 2 of the roof window 1. To that end, the second bracket leg 62 comprises engagement means to interact with a corresponding receiving structure in an outer side of the side frame member 22 of the frame 2 of the roof window 1. This ensures that the mounting bracket 6 is positioned correctly on the side frame member 22 and facilitates the installation process. The positioning of the mounting bracket 6 may be indicated in both the longitudinal direction and the height direction of the side frame member 22, for instance by suitable markings and/or holes. The first bracket leg 61 of the mounting bracket 6 is connected to the second bracket leg 62 via a bend 614.

In the embodiment shown, the second bracket leg 62 is provided with a first engagement means 624 in a first section 621 of the second bracket leg 62 and a second engagement means 629 in a second section 626 of the second bracket leg 62.

Of these two engagement means 624, 629, the second engagement means 629 is configured to assume an inactive position and an active position, of which the active position is shown.

The first engagement means 624 is configured to be received in one receiving structure of the outer side of the frame member 22 in the mounted condition of the mounting bracket 6 on the frame 2 of the roof window 1, and the second engagement means 629 is configured to be received in another receiving structure of the outer side of the frame member 22 in the mounted condition of the mounting bracket 6 on the frame 2 of the roof window 1 in its active position only. This is shown most clearly in FIG. 4, in which the first engagement means 624 is received in a first outer groove 27, and the second engagement means 629 is received in a second outer groove 27b. At least the side frame members 22, 23 each comprises a plurality of receiving structures at an outer side of the respective side frame member, such that at least one of the receiving structures interacts with the mounting bracket 6 in the mounted condition of the roof window 1. The first outer groove 27 and the second outer groove 27b both extend in the longitudinal direction of the side frame member 22 at a distance from each other in the height direction, the first outer groove 27 being located to the exterior of the second outer groove 27b, as seen in the height direction.

To bring the second section 626 with the second engagement means 629 from the position in an aperture 620 in the second bracket leg 62 to a position in which the second section 626 is located substantially in extension of the first section 621, the second section 626 with the second engagement means 629 is connected to the first section 621 via a hinge connection 625, such that the second section 626 is configured to be brought from the inactive position to the active position by rotating the second section 626.

In the embodiment shown, each of the first and second engagement means comprises a flange 624, 629 protruding at substantially right angles from the respective first and second sections 621, 626. Alternative configurations such as discrete spikes are also conceivable.

Hinge Assembly and Coupling Unit—FIGS. 6 to 7 and 22 and 23

Referring first to FIGS. 6 and 7 it is shown that the roof window 1 furthermore comprises a hinge assembly 9.

The hinge assembly 9 is configured in such a way that it allows the sash 3 to be tophung in a first operational condition corresponding to normal use. That is, during normal use the sash 3 is rotated about a substantially horizontal first hinge axis at or near the top frame member 21 and top sash member 31 between a closed position and an open position.

Referring now also to FIGS. 22 and 23, it is seen that the hinge assembly 9 comprises a hinge unit 91 with a frame hinge part 92 connected to or connectable to at least the top frame member 21, a sash hinge part 93 connected to at least the top sash member 31, and a hinge pin 94 connecting the frame hinge part 92 with the sash hinge part 93.

The term “connected to” implies that the component in question is in a condition, state or position in which the component in question is in fact connected to a part, whereas “connectable to” is intended to encompass such conditions, states and positions in which the component in question may be connected to the relevant part, but is not necessarily in connection with the part. In the description of FIGS. 22 and 23, the frame hinge part 92 including any sub-components will be described as being connected to parts of the frame 2.

In the following, a coupling unit 95 of the hinge assembly 9 will be described in some detail. Details of the hinge assembly 9 are described in more detail in Applicant's co-pending patent applications filed on the same date as the present application.

The coupling unit 95 is configured to allow selective coupling of at least the frame hinge part 92 of the hinge unit 91 to the top frame member 21 and optionally to one of the side frame members 22, 23. In the following, the coupling unit 95 will be described as comprising both a top frame coupling plate 96 and a side frame coupling plate 97. Alternative configurations are conceivable.

The top frame coupling plate 96 comprises a base section 961 connected to an inner side of the top frame member 21. The top frame coupling plate 96 is connected to the top frame member 21 by means of a plurality of fastening means including at least one spigot 961c on the base section 961 and two bolt elements functioning also as engagement pins 962, 963. In this case, each engagement pin 962, 963 cooperates with an insert nut 982, 983 on the outer side of the top frame member 21. To accommodate the top frame coupling plate 96, the top frame member 21 comprises a hinge assembly receiving milling 29a and a set of openings 29c, 29e of which openings 29e are through-going openings, or through-holes.

The side frame coupling plate 97 comprises a base section 971 and is connected to the inner side of the side frame member 22 by means of a plurality of fastening means including at least one spigot 971c on the base section 971 and at least one opening (not shown in detail) for fastening means such as screws 981. To receive the side frame coupling plate 97, the side frame member 22 comprises a hinge assembly receiving milling 29b and a set of openings 29d, 29f.

Operating Assembly—FIGS. 8 and 10

During normal use, i.e. when the roof window 1 has been installed, and a user wishes to put the sash 3 in a ventilating position, the opening, closing and parking may be carried out by the assistance of an operating assembly, for instance as the shown manual handwinder or screwjack constituting the operating assembly 5.

Referring first to FIG. 8, the operating assembly 5 comprises a sash fitting 55, a spindle part 52 with a spindle 521 connected to a socket fitting 51 via a nut part 53, and a handle 522, the sash fitting 55 being connected to the bottom

sash member 34 and the socket fitting 51 being connected to the bottom frame member 24 in a mounted condition of the operating assembly such that upon rotation of the spindle part 52 relative to the nut part 53, the bottom sash member 34 is moved relative to the bottom frame member 24.

In the embodiment shown, the roof window 1 may be provided in a supply condition which is suitable for packaging and transportation, the sash fitting 55 is connected to the bottom sash member 34 of the roof window 1 whereas the spindle part 52 with the nut part 53 and the socket fitting 51 are provided separately from the roof window 1.

The nut part 53 comprises a nut ring 531 connected to a set of flanges 512 protruding from a base plate 511 of the socket fitting 51, here by means of a set of bolts 532. Holes 513 are provided in the base plate 511 for mounting the socket part 51 to the bottom frame member 24.

The operating assembly 5 furthermore comprises a split 56 associated to the sash fitting 55, the split 56 being displaceable between an active position in which it is in engagement with a set of openings 553 in a set of flanges 552 protruding from a base plate 551 of the sash fitting 55 and an inactive position to reveal a reception gap between the flanges 552 of the sash fitting 55.

The spindle part 52 comprises an end portion 54 configured to cooperate with the sash fitting 55 in the mounted condition.

Sash and Frame Structure—FIGS. 5 to 16

As shown in the cross-sectional view of the bottom part of the roof window 1 in FIGS. 8 and 9, the pane 4 comprises an exterior sheet 41 and at least one interior sheet, here two interior sheets 42, 43 placed in contact with each other. The pane 4 is here a so-called stepped pane in which the exterior sheet 41 comprises an extended portion 41a extending beyond a bottom edge portion 42b of the interior sheets 42, 43 to a bottom edge portion 41b of the exterior sheet 41. Referring now also to FIGS. 4 and 5, showing side and top parts of the roof window 1, respectively, the pane 4 has a common side edge portion 4b—this applies also to the opposite, not-shown side—and a common top edge portion 4c. A spacer 47 is provided between the most exterior interior sheet 42 and the exterior sheet 41 along all edge portions.

Common to all sash members 31, 32, 33, 34 of the sash 3 according to the invention is that each sash member comprises a profile element 31a, 32a, 34a, an inner element 31c, 32c, 34c and an intermediate element 31b, 32b, 34b. Although not indicated, the side sash member 33 not shown in cross-section has a similar configuration as the shown side sash member 32.

The intermediate element 31b, 32b, 34b of the respective sash member 31, 32, 33, 34 forms a connection between the profile element 31a, 32a, 34a and the inner element 31c, 32c, 34c of the sash member 31, 32, 33, 34 in question. The intermediate elements 31b, 32b, 34b of the sash members 31, 32, 33, 34 may in principle be formed in the same way for all four sash members, or be formed with individual properties. Typically, the two side sash members 32, 33 of the sash 3 will be designed with equal properties though.

Referring also to FIG. 12a, the intermediate elements 31b, 32b, 33b of the top sash member 31 and the two side sash members 32, 33, in the embodiment shown, are formed as a set of longitudinal profiles while the intermediate element 34b of the bottom sash member 34 comprises a set of separate fittings, described in greater detail in connection with FIGS. 14a-b. Details of the respective intermediate elements 31b, 32b, 33b, 34b will be described below.

The inner elements 31c, 32c, 33c, 34c of the sash members 31, 32, 33, 34 form a coherent inner element sash structure supporting an interior edge portion of the pane 4. That is, edge portions of the pane 4 partly overlap the inner elements 31c, 32c, 33c, 34c as seen from the interior. In this way, the top edge portion 4c, the side edge portion 4b, and the opposite side edge portion, and the bottom edge portion 42b of the interior sheet 42 are all located on the outer side of the coherent sash structure provided by the inner elements 10 such that any spacers 47 and other elements present along the edge portions of the pane 4 are hidden from view by the inner elements 31c, 32c, 33c, 34c and are thus not visible from the interior of the building. The inner elements 31c, 32c, 33c, 34c of the sash members 31, 32, 33, 34 may have 15 a substantially identical cross-sections and be formed by any suitable material, for instance wood, joined in mortise joints at the corners. It is also conceivable to form the inner element structure as a fully coherent structure, for instance by moulding.

20 As will also be described in further detail in connection with the embodiment below, the profile elements 31a, 32a, 33a, 34a of the sash members 31, 32, 33, 34 are located along respective exterior edge portions of the pane 4, and the intermediate element 31b, 32b, 33b, 34b of each sash member 31, 32, 33, 34 comprises engagement means 32b3, 34b3 configured to form a structural connection with the inner element 32c, 34c in one of at least two distinct positions in the height direction.

25 Also indicated in FIGS. 5 and 6 is a hinge assembly 9 present in a gap between the top sash member 31 and the top frame member 21, and between the side sash member 32 and the side frame member 22, by which the sash 3 is connected to the frame 2 to provide a tophung hinge connection.

30 Regarding the frame 2 of the roof window 1, each frame member 21, 22, 23, 24 comprises a plurality of receiving structures at an interior, exterior, inner and/or outer side of the respective frame member. Each receiving structure is 35 configured to interact with auxiliary equipment in an assembled condition of the frame 2.

30 In the embodiment shown, the top frame member 21 and the two side frame members 22, 23 have substantially identical cross-sections.

35 Referring particularly to FIGS. 8 and 9, the bottom frame member 24 comprises an outer piece 24a and a separate inner piece 24b. The outer piece 24a and the separate inner piece 24b may be formed by the same material as the top frame member 21 and the side frame members 22, 23, for instance wood, or as a composite component comprising plywood and other materials.

40 A further feature of the roof window 1 in the shown embodiment is that the frame 2 comprises at least one releasable component configured to allow replacement with a different set of components to change the functionality of the roof window 1.

45 In the embodiment shown, one such releasable component comprises a cover 24c releasably connected to remaining components of the bottom frame member 24 and defining a cavity relative to the remaining components of the bottom frame member 24. The cover 24c may be formed by 50 any suitable material, for instance a profile element of a plastic or metal material.

55 Here, where the bottom frame member 24 comprises the outer piece 24a and the separate inner piece 24b, the cavity defined by the cover 24c is defined by the inner side of the outer piece 24a in the outwards direction and mainly by the exterior side of the separate inner piece 24b towards the interior.

11

To obtain the releasable connection, edge portions **24c1**, **24c2** of the cover **24c** are received in receiving grooves in the bottom frame member **24**, specifically in one receiving groove **24a1** in the outer piece **24a** and one receiving groove **24b1** in the separate inner piece **24b**.

In the embodiment shown, in which the roof window **1** is prepared for manual operation by means of the operating assembly **5**, an insulating piece **24d** is accommodated in the cavity defined by the cover **24c**.

In order to change the functionality of the roof window **1**, the cavity defined by the cover **24** is configured to receive an electrical operator (not shown) and the cover **24** is configured to be replaced by a different cover (not shown) allowing operating means of the electrical operator to be connected to the sash **3**.

It is also conceivable to allow the sash fitting **55** connected to the bottom sash member **34** to be selectively connected to such an electrical operator in which case the sash fitting **55** is simply reused for the operating means of the electrical operator.

Likewise, it is conceivable to provide the roof window **1** in a condition in which the bottom frame member **24** comprises a dummy element configured to be replaced by the socket fitting **51** of the operating assembly **5**.

Correspondingly, if the roof window **1** were provided in a basic form with a different hinge than the hinge assembly **9** described in the above embodiments, it would also be conceivable to use blind plates to cover the hinge assembly receiving millings **29a**, **29b** to allow replacement of the previous hinge with the hinge assembly **9**.

A first receiving structure comprises a lining groove **25** in an interior side of each frame member **21**, **22**, **23**, **24**. The lining grooves **25** are configured to interact with a set of interior lining panels. Such lining panels typically form the transition between the roof window **1** and an interior wall. In the bottom frame member **24**, a first groove portion **25a** is provided in the outer piece **24a** and a second groove portion **25b** in the separate inner piece **24b**. In the assembled condition of the frame **2**, the first and second groove portions **25a**, **25b** form the lining groove **25**.

In the embodiment shown, each frame member **21**, **22**, **23**, **24** comprises an inwards protruding portion **21i**, **22i**, **24i** at least partly overlapping the corresponding sash member **31**, **32**, **33**, **34**, as seen from the interior. This is made possible, since all parts of the sash **3** move towards the exterior when opening the sash **3** relative to the frame **2**.

A second receiving structure comprises a sealing groove **26** in an exterior side of the inwards protruding portion **21i**, **22i**, **24i**. The sealing groove **26** is configured to interact with a frame sealing profile **26p**.

A third receiving structure comprises a first outer groove **27** in an outer side of the frame member **21**, **22**, **23**, **24**. The first outer groove **27** is configured to interact with a respective piece **71**, **72**, **73**, **74** of the insulating frame **7**. The interaction may take place by introducing a longitudinal protrusion **78** of the insulating frame piece into the groove **27**, or to locate separate fastening means correctly.

Taking again the perspective as seen from a user from the interior of the building, in the roof of which the roof window **1** is installed, it is also noted that the inwards protruding portion **21i**, **22i**, **24i** of each frame member **21**, **22**, **23**, **24** has an inwards facing surface which together form a coherent inwards facing surface. As indicated, this appearance mimics a corresponding coherent inwards facing surface of the sash **3**.

A fourth receiving structure comprises an interface unit groove **28** in an exterior side of the top frame member **21** and

12

the two side frame members **22**, **23**. This interface unit groove **28** interacts with a respective top and side element **81**, **82**, **83** of an interface unit **8**, the function of which will be described further below.

Further details visible in the drawings include guiding elements **22g** (see FIG. 7) and **32g** (see FIG. 10), which ascertain that the sash **3** is aligned relative to the frame **2** when closing the sash such that any skewness occurring in the open position of the sash **3** is eliminated. A screening mounting bracket **32s** is visible in FIG. 8, by which it is possible to install an interior screening device (not shown) in the sash **3** to provide screening of the pane **4**. An abutment element **22s** provides a stop for the bottom sash member **34** during closing.

Details of the insulating frame **7** are also shown in these figures; as mentioned in the above, the insulation frame **7** includes top piece **71**, side pieces **72**, **73**, and bottom piece **74**. In the embodiments shown, each such insulation frame piece comprises protrusion **78** to be received in the outer side of the respective frame member, and an indentation **75** to interact with auxiliary equipment in the form of an underroof collar described in more detail in Applicant's co-pending patent applications filed on the same date as the present application. With particular reference to FIG. 11, a recess **76** is shown which makes place for the mounting bracket **6** to be mounted on the side frame member **23** of the frame **2**, and a folding line **77** which allows folding back of part of the side piece **73** of the insulating frame **7** to allow access to the outer side of the side frame member **23**. At least 30 the side pieces **72**, **73** of the insulating frame **7** are provided with such recesses **76** and folding lines **77** at or near the location of the intended positions of the mounting brackets **6** of the set of mounting brackets supplied with the roof window **1**. The insulating frame **1** may in principle be made 35 from any material with suitable thermal insulating properties. It is presently preferred that a foam material be used, for instance polyethylene foam.

Intermediate Elements—FIGS. 5 to 16

Turning now to the description of the connection between 40 the elements of the sash **3**, the engagement between the intermediate elements **31b**, **32b** and **33b** of the top sash member **31** and the two side sash members **32**, **33** and the respective inner element **31c**, **32c**, **33c** will be described first.

With particular reference to FIG. 16, an outer side of each 45 inner element, here as shown the inner element **32c** of the side sash member **32**, is provided with reception means configured to receive the engagement means of the intermediate element **32b** of the side sash member **32**.

In the embodiment shown, the reception means comprises 50 two longitudinally extending grooves **32c1**, **32c2** at a distance from each other in the height direction, the grooves being open in an outwards direction of the roof window **1**.

In the embodiment shown, the longitudinal profiles forming 55 the intermediate elements **31b**, **32b**, **33b** have a uniform cross-section and may in principle be cut from one and the same profile length. It is preferred that the longitudinal profiles are formed by a continuous moulding process, such as extrusion or pultrusion. Specifically the profiles are 60 formed by pultrusion of a composite material incorporating resin and glass fibre.

Thus, only one of these intermediate elements will be 65 described in detail, namely intermediate element **32b**. Referring now to FIG. 15, the intermediate element **32b** comprises a base portion **32b1** extending substantially in the height direction in the assembled condition of the sash **3** and a head portion **32b2** extending at an angle to the base portion **32b1**.

13

The base portion **32b1** is provided with the engagement means on a surface facing inwards in the assembled condition, facing an outer surface of the inner element **32c**, as shown in FIG. 16. The position, location and length of the individual intermediate elements **31b**, **32b** and **33b** appear also from FIGS. 3, 4, 5, 10 and 12a.

In the embodiment shown, the engagement means of the base portion **32b1** of the intermediate element **32b** comprises a protruding portion formed as a flange **32b3** extending throughout the length of the profile and configured to engage with a selective one groove **32c1**, **32c2** of the inner element **32c** of the side sash member **32**.

The base portion **32b1** of each intermediate element **32b** comprises a stepped section **32b4**, which is offset in the inwards direction by an offsetting bend **32b5** relative to the remaining section of the base portion **32b1**. The engagement means, here the flange **32b3**, is provided in the stepped section **32b4**.

Additional fastening means **30x** (cf. FIGS. 12a and 16) are provided to fasten the intermediate element or elements **32b** to the inner element **32c** of the side sash member **32**. In order to receive the additional fastening means **30x**, the base portion **32b1** of the intermediate element **32b** comprises openings **32b6** configured to receive the additional fastening means **30x**, namely in the stepped section **32b4**.

Turning now in particular to FIGS. 14a and 14b, the connection between the intermediate element **34b** and the inner element **34c** of the bottom sash member **34** will be described in detail.

Just as the intermediate elements **31b**, **32b**, **33b** described in the above, the intermediate element **34b** comprises a base portion **34b1** extending substantially in the height direction and a head portion **34b2** extending at an angle to the base portion **34b1**. The base portion **34b1** is provided with the engagement means **34b3** on an inner surface, facing an outer surface of the inner element **34c**. The engagement means of the base portion **34b1** comprises a protruding portion **34b3** to engage with a selective one groove **34c1**, **34c2** of the inner element **34c** of the bottom sash member **34**. Additional fastening means **30y** are provided to fasten the intermediate element **34b** to the inner element **34c** of the bottom sash member **34**, in openings **34b6** in stepped section **34b4**, which is offset in the inwards direction by offsetting bend **34b5** relative to the remaining section of the base portion **34b1**.

In the embodiment shown, the intermediate element **34b** of the bottom sash member **34** comprises a set of fittings. Two such sets may be provided along the length of the bottom sash member **34**.

Each set of fittings comprises a connecting fitting provided with the engagement means configured to form a structural connection with the inner element **34c** in one of at least two distinct positions in the height direction. The connecting fitting comprises a first fitting part **34b0** and a second fitting part **34b10**. The first fitting part **34b0** comprises the engagement means and the second fitting part **34b10** is configured to be connected to the first fitting part **34b0** to function as a spacer between the outer surface of the inner element **34c** of the bottom sash member **34** and the first fitting part **34b0**. To connect the first and second fitting parts **34b0**, **34b10** with each other, the second fitting part **34b10** is provided with at least one resilient hook **34b11** configured to interact with a corresponding opening **34b12** in the first fitting part **34b0**. The head portion **34b2** of the intermediate element **34b** of the bottom sash member **34** is received in a

14

slit **34a5** of an inner portion **34a2** of the profile element **34a** of the bottom sash member **34** in the assembled condition of the sash **3**.

Comparison Embodiments—FIGS. 17 and 18

Turning now to FIGS. 17 and 18, showing a simplified overview of the main components of the side sash member **32**, it is seen how the same components of the sash **3** may accommodate two different thicknesses of the pane **4**. This is carried out by changing the position of the engagement means of the intermediate element **32b** from the first groove **32c1** to the second groove **32c2**. This will require a slightly adapted side frame member **22c**. The intermediate elements **31b**, **33b**, **34b** at the other sash members **31**, **33**, **34** are moved similarly.

Profile Elements—FIGS. 19 to 21

Focus will now be on the profile elements of the sash **3**. The general configuration of the profile elements **31a**, **32a** and **33a** of the top and side sash members **31**, **32**, **33** is shown in the perspective views of FIGS. 3 to 6 and 10 while details are shown in the cross-sectional view of FIG. 16. The profile element **34a** of the bottom sash member **34** is shown most clearly in FIGS. 12a to 14b.

Corresponding to the above, only the profile element **32a** of the side sash member **32** will be described in representation of the longitudinal profiles of the top sash member **31** and the two side sash members **32**, **33**, since in the embodiment shown, these profile elements are formed as a set of longitudinal profiles of substantially uniform cross-section.

The details common to all profile elements **31a**, **32a**, **33a**, **34a** are as follows:

Each profile element **32a**, **34a** comprises a head portion **32a1**, **34a1** and an adjoining outer portion **32a3**, **34a3**.

The head portion **32a1**, **34a1** is substantially parallel to the plane of the roof window **1** in the assembled condition of the roof window **1**, and the adjoining outer portion **32a3**, **34a3** is substantially perpendicular to the head portion **32a1**, **34a1**.

However, the head portion **32a1** of the profile element **32a** of each of the top and side sash members **31**, **32**, **33** is located on the exterior side of the exterior pane surface **4e**, and on the outer side of the side edge portion **4b** and the top edge portion **4c** of the pane **4**, whereas the head portion **34a1** of the profile element **34a** of the bottom sash member **34** is located on the interior side of the extended portion **41a** of the exterior sheet **41** of the pane **4**.

The profile element **32a** of the side sash member **32** and the profile element **34a** of the bottom sash member **34** are thus separated by a layer of glass; nevertheless, an overlap is provided by selecting a length of the profile elements **32a**, **33a** of the two side sash members **32**, **33** to substantially correspond to or slightly exceed the distance between the top edge portion **4c** of the pane **4** and the bottom edge portion **41b** of the exterior sheet **41** of the pane **4**. The length of the profile element **34a** of the bottom sash member **34** is suitably selected to extend substantially to the side edge portion **4b** of the pane **4**.

The length of the profile element **31a** of the top sash member **31** is chosen in accordance with the dimensions of the pane **4** and the desired manner of joining the profile element **31a** to the profile elements **32a**, **33a**. In the embodiment shown, the longitudinal profiles form mitred joints between the profile element **31a** of the top sash member **31** and the respective profile element **32a**, **33a** of the side sash members **32**, **33** in the assembled condition of the sash **3**, see FIG. 19.

15

Also visible in FIGS. 12a to 13b are an end plug 38 which closes off the profile element 32a of the side sash member 32. The end plug 38 is provided with friction-increasing ribs and a snap arm, not described in detail. The glazing bar 45 is provided with a counterpart end plug. Furthermore, a trailing element 37 is provided to drain any condensed water out to a profile element sealing 34p.

To ensure a tight joint at the mitred joints, a corner key 39 is provided at each mitred joint, see FIGS. 19-21. During manufacture, a sealant 39b is suitably applied as will be described in further detail below with particular reference to FIGS. 19 to 21.

The corner key 39 has a generally L-shaped configuration with two perpendicular legs 39a1 divided by a channel 39a2. In the channel 39a2, a set of primary openings 39a3 is provided.

Furthermore, each leg 39a1 is adjoined by a depending skirt 39a4 on a first side. Here, a secondary opening 39a5 is provided.

In order to fit the profile of the profile elements 31a, 32a, 33a, each leg 39a1 is adjoined by an inclined section 39a6 on a second side.

As shown in FIGS. 20 and 21, the channel 39a2 ends in a tongue 39a7, optionally adjoining an inclined channel section 39a8.

The profile elements 31a, 32a, 33a are suitably configured to receive the pane 4 in an upside-down position, i.e. with the respective head portions 32a1 facing a substrate such as an assembly table. This step of the assembly of the sash 3 may take place after the intermediate elements 31b, 32b, 33b have been introduced into the respective profile elements 31a, 32a, 33a. Also visible in FIGS. 16 and 19, are pane clips 4t, which are placed at suitable distances from each other along the top edge portion 4c and side edge portions 4b of the pane 4. In the embodiment shown, the interaction between the main components of the sash 3 is defined by the following configuration of the components:

Each of the longitudinal profiles forming the profile elements 31a, 32a, 33a of the top sash member 31 and the two side sash members 32, 33 comprises an inner portion 32a2 adjoining the head portion 32a1. The dimensions are chosen such that the inner portion 32a2 overlaps the pane 4 in the assembled condition of the sash 3.

The head portion 32a1 of each profile element 31a, 32a, 33a is configured to protrude to the exterior relative to the exterior surface of the pane 4e in the assembled condition of the sash 3.

The inner portion 32a2 is inclined from the head portion 32a1 relative to the head portion 32a1 and extends inwards and to the interior, towards the exterior surface of the pane 4e in the assembled condition of the sash 3.

The inner portion 32a2 is adjoined by a first bend 32a4 configured to be located at or near the exterior surface of the pane 4e.

A second bend 32a5 is provided as shown in for example FIG. 16. The second bend 32a5 has as its function to accommodate a sealing 4p relative to the exterior surface of the pane 4e.

A third bend 32a6 is also provided, said third bend 32a6 being configured to accommodate an inner edge portion 32b9 of the intermediate element 32b relative to an interior side of the inner portion 32a2. For a detailed overview of the intermediate element 32b, confer FIG. 15.

A transition portion 32a7 is provided between the head portion 32a1 and the inner portion 32a2. The transition portion 32a7 is configured to accommodate a ridge portion 32b7 of the intermediate element 32b.

16

A fourth bend 32a8 is provided adjacent the outer portion 32a3 of the profile element 32a. The fourth bend 32a8 is configured to accommodate an outer edge portion 32b12 of the intermediate element 32b.

The inner portion 32a2 of the profile element 32a is configured to be located opposite an inner inclined portion 32b8 of the intermediate element 32b in the assembled condition of the sash 3.

Finally, the outer edge portion 32b12 of the intermediate element 32b is associated with the head portion 32b2 of the intermediate element 32b via an outer inclined portion 32b11 and a bend 32b10.

All in all, the configuration of the described embodiment makes it possible to provide a secure engagement between the intermediate elements 31b, 32b, 33b and the profile elements 31a, 32a, 33a.

The length of the intermediate elements 32b, 33b of the side sash members 32, 33 may be chosen slightly shorter than the associated profile elements 32a, 33a.

At the bottom sash member 34, the head portion 34a1 of the profile element 34a is provided with at least one longitudinally extending groove 34a4 to receive a respective sealing strip 4s. These sealing strips 4s may be formed by silicone to form an adhesive connection between the profile element 34a and the extended portion 41a of the exterior sheet 41 of the pane 4. A masking 44 may be provided at the extended portion 41a on in interior side of the exterior sheet 41.

As described in the above, the intermediate element 31b, 32b, 33b, 34b of each sash member 31, 32, 33, 34 comprises engagement means 32b3, 34b3 configured to form a structural connection with the inner element 31c, 32c, 33c, 34c. To secure the intermediate element 34b of the bottom sash member 34 also to the profile element 34a, the head portion 34b2 of the intermediate element 34b is configured to be received in a slit 34a5 of an inner portion 34a2 of the profile element 34a of the bottom sash member 34 in the assembled condition of the sash 3, see FIGS. 14a-b. To increase the strength of the inner portion 34a2, this portion may be formed as a double-layer, folded portion.

The manufacture of the sash 3 may in principle take place in any suitable manner. In the following, one presently preferred method will be described:

In a first step, a set of three longitudinal profiles is provided. The longitudinal profiles may for instance be formed a single profile length of an extruded material such as metal, for instance aluminium. Other materials and manufacturing processes are conceivable, including roll forming of steel or other metal, or of a composite material.

Secondly, mitre shapes are formed at mutually facing ends of the longitudinal profiles. If the longitudinal profiles are formed from a single length, and if convenient, the mitre shapes may be formed in a coherent length by aptly formed incisions to form inner corners at the intersection between the top and the sides.

A pane of suitable dimensions is provided, for instance as described in the above.

The sets of four inner elements and four intermediate elements are provided, for instance as described in the above.

The longitudinal profiles are now placed in an upside-down position on an assembly table to form a profile element frame structure constituting three sides of a rectangle. This typically takes place by guiding elements fixable to the assembly table corresponding to the outer circumference of the sash.

The pane is placed within the profile element frame structure, and the profile element structure is connected to the inner elements, optionally via the intermediate elements, to form the sash. During this procedure, the intermediate elements at the top and sides are typically inserted into the counterpart profile elements. The inner elements may as described above be connected to each other to form an inner element frame structure, which is placed on the pane, following which the intermediate elements are connected to the respective inner elements.

Referring briefly back to FIGS. 19 to 21, a set of two corner keys 39 is advantageously provided placed within the longitudinal profile elements 31a, 32a, 33a at the mutually facing mitred ends before placing the pane 4 within the profile element frame structure. Sealant 39b is preferably applied to each corner key 39. During assembly, it is ensured that the sealant 39b is able to flow through the primary openings 39a3 of the corner key 39 such that the sealant 39b is distributed.

In the embodiment shown, each corner key 39 is configured to be mechanically connected to the respective adjacent profile elements 31a, 32a, 33a. This may take place by clinching, for instance by TOX® technology.

In embodiments in which the roof window 1 comprises one or more glazing bars, such as glazing bar 45, the glazing bar or bars is/are aligned on the assembly table before placing the pane 4 within the profile element frame structure. The glazing bar 45 is provided with one or more adhesive strips 45a to fasten to the exterior surface 4e of the pane 4. Sealing Assembly and Interface Unit—FIGS. 24 to 36

Referring now in particular to FIGS. 24 to 29a, an embodiment is shown in which the roof window 1 is provided with a covering assembly 10. Details of the covering assembly 10 generally comprising a flashing assembly and any other auxiliary equipment are described in more detail in Applicant's co-pending patent applications filed on the same date as the present application.

In the following, a sealing assembly of the roof window 1 will be described. Some details of the sealing assembly have been described in the above as well.

The sealing assembly generally comprises a set of sealing profiles.

In the embodiment shown, sealing between the sash 3 and the frame 2 is provided by an exterior sealing plane, an intermediate sealing plane and an interior sealing plane. Reference is also made to the cross-sectional views of the top, side and bottom of the roof window 1 shown and described in the above.

The interior sealing plane comprises the frame sealing profile 26p provided in the exterior side of each frame member 21, 22, 23, 24 and interacts with the interior side of the respective sash member 31, 32, 33, 34.

The intermediate sealing plane comprises the sash sealing profile 30p1 provided in the outer side of each sash member 31, 32, 33, 34 and interacts with the inner side of the respective frame member 21, 22, 23, 24. The sash sealing profile 30p1 is provided in sash sealing groove 30g1.

At the bottom side, the exterior sealing plane is provided in that the profile element sealing 34p on the profile element 34a of the bottom sash member 34 is in contact with the outer side of the bottom frame member 34 in the closed position of the sash 3.

At the top and sides, the exterior sealing plane is defined by the interface elements 81, 82, 83. Referring in particular to FIGS. 26 and 27, the similarities and differences between

the top interface element 81 and the side interface elements, here represented by interface element 82, in the embodiment shown will be described:

Each interface element 81, 82 comprises a base portion 80 with an anchor section 801, an inner leg 86, an outer leg 87, a flange 88 and a sealing portion 89. The anchor section 801 of the base portion 80 is received in the interface unit groove 28 in the assembled condition of the roof window 1. The sealing portion 89 faces to the exterior and interacts with the top sash member 31 and side sash members 32, 33 during opening and closing of the sash 3 and in the closed position of the sash 3.

Together, the inner leg 86, the outer leg 87, and the flange 88 form a channel 810, 820 in the top interface element 81 and the side interface element 82. A corresponding channel is formed in the other side interface element 83. In this way, water emanating from rain or other precipitation may be guided from the channel 810 in the top interface element 81 to the channels 820 in the side interface elements 82, 83 and further out to the covering assembly 10 (not shown in detail).

Common to both the top interface element 81 and the side interface element 82 in the embodiment shown is that the sealing portion 89 comprises an inner sealing lip 891 and an outer sealing lip 892. The inner sealing lip 891 of both the top interface element 81 and of the side interface element 82 is provided sufficiently inwards that the inner sealing lip 891 interacts with the interior of the top sash member 31 and the side sash member 32, cf. FIGS. 6 and 5; however the outer sealing lip 892 of the top interface element 81 is located on the outer side of the top sash member 31. In the embodiment shown, this is due to the fact that the flange 88 of the top interface element 81 is longer than the counterpart flange of the side interface element 82. It is noted that while at least the sealing portion 89 of each interface element 81, 82, 83 is formed to be resilient, i.e. as is customary in sealings, the sealing portion 89 is able to be deformed when coming into abutment with another component and then spring back when relaxing, this is not reflected in the figures since they generally show elements in their undeformed condition. In general, at least the sealing portion 89 has different properties than at least the base portion 80. This may be provided by co-extrusion or co-moulding of two (or more) different materials.

To ensure a tight interaction at the top of the roof window 1, the top interface element 81 comprises an additional inner sealing lip 893, a first additional outer sealing lip 894 and a second additional outer sealing lip 895, cf. also FIG. 28.

In the embodiment shown, the interface elements 81, 82, 83 furthermore allow interaction with the covering assembly 10 in that the base portion 80, inner leg 86 and flange 88 form a flashing reception groove 85. The flashing reception groove 85 has a groove opening 85b and is provided with a number of protrusions 85a.

The sealing assembly furthermore comprises a pane sealing 30p2, received in pane sealing groove 30g2. It is noted that the pane sealing 30p2 remains stationary relative to the sash 3.

Referring now to FIGS. 29b to 36, details of alternative embodiments will be described. Only differences relative to the above-mentioned embodiment will be described in detail.

In FIG. 29b, a foam element 32f is shown present in the sash side member 32. A similar foam element may be present in the opposite sash side member 33 as well. The longitudinal extension of the foam element 32f may be such that the foam element 32f extends over a major part of the

length of the sash side member 32. The foam element 32f abuts the interior side of the head portion 32b2 of the intermediate element 32b along the extent of the intermediate element 32b, and is allowed to expand towards the interior side of the head portion 32a1 of the profile element 32a of the side sash member 32 in the portions of the foam element 32f protruding beyond the longitudinal ends of the intermediate element 32b. The foam element 32f has general climate shielding properties.

In FIG. 30, a stabilising plate 310x is placed in the channel 810 of the top element 81 of the interface unit 8 to improve the structural properties. Furthermore, an extension plate 310y is shown fastened to the profile element 31a of the top sash member 31 to protrude into the channel 810. The extension plate 310y improves guidance of precipitation into the channel 810 and for further guidance towards the sides of the roof window. This is particularly relevant in roof windows built into roofs of a large inclination. The relative positions of the stabilising plate 310x and the extension plate 310y are shown more clearly in FIG. 32. For ease of reading of the relevant portions of the interface unit 8, FIG. 33 shows the top element 81 of the interface unit 8 without the stabilising plate 310x and without the sash 3 including the extension plate 310y.

FIG. 31 shows the interaction between the bottom of the roof window 1 and the covering assembly 10.

Finally, FIG. 34 show a view of the lower right-hand corner of the roof window 1, in which the sash 3 has been lifted slightly relative to the frame 2 for clarity reasons.

Here, a clip 22x is mounted on the side element 82 of the interface unit 8. The clip 22x is provided with a clip flange 22xa as shown in more detail in FIG. 36. The end plug 38 of the sash side member 32 is in this embodiment provided with an end plug flange 38a. In the closed position of the roof window 1, the end plug flange 38a overlaps the clip 35 flange 22xa.

In general, components of the roof window are easily disassembled and each component may in principle be reused, be recycled by appropriate environmentally responsible disposal means, or the material be recovered for other uses.

The invention claimed is:

- 55 1. A method of manufacturing a roof window comprising a frame, a sash, and a pane, in which the frame comprises a set of frame members including a top frame member, two side frame members and a bottom frame member and the sash comprises a set of sash members including a top sash member, two side sash members and a bottom sash member, each frame and sash member defining a longitudinal direction, and the pane comprises a number of edge portions and an exterior pane surface defining a plane of the roof window in an assembled condition of the roof window, each sash member comprising a profile element, an inner element and an intermediate element forming a con-

23

nection between the profile element and the inner element of each sash member in an assembled condition of the sash,
 the profile elements of the sash members being located along respective exterior edge portions of the pane in the assembled condition of the sash, and
 the profile elements of the top sash member and the two side sash members being formed as a set of longitudinal profiles of substantially uniform cross-section, comprising the steps of:
 providing the set of longitudinal profiles,
 forming mitre shapes at mutually facing ends of profiles of the set of longitudinal profiles,
 providing the pane,
 providing a set of four of the inner elements,
 providing a set of four of the intermediate elements,
 providing a set of two generally L-shaped corner keys with two perpendicular legs divided by a channel,
 placing the set of longitudinal profiles in an upside-down position on an assembly table to form a profile element frame structure constituting three sides of a rectangle, placing a respective corner key within the longitudinal profiles of the set of longitudinal profiles at the mutually facing mitred ends,
 placing the pane within the profile element frame structure, and
 connecting the profile element structure to the inner elements via the intermediate elements.

2. The method of claim 1, whereby a sealant is applied to each corner key.

3. The method of claim 2, whereby each corner key is mechanically connected to the respective adjacent profile elements by means of clinching.

4. The method of claim 1, whereby the roof window comprises at least one glazing bar, and whereby the at least one glazing bar is aligned on the assembly table before placing the pane within the profile element frame structure.

5. The method of claim 1, whereby the set of three longitudinal profiles are provided from a single profile length and the set of three longitudinal profiles are coherent.

6. A roof window comprising a frame, a sash, and a pane, in which

the frame comprises a set of frame members including a top frame member, two side frame members and a bottom frame member and the sash comprises a set of sash members including a top sash member, two side sash members and a bottom sash member, each frame and sash member defining a longitudinal direction, and the pane comprises a number of edge portions and an exterior pane surface defining a plane of the roof window in an assembled condition of the roof window, each sash member comprising a profile element, an inner element and an intermediate element forming a connection between the profile element and the inner element of each sash member in an assembled condition of the sash, wherein a vertical plane extending perpendicular to the pane and passing through an upper portion of the intermediate element does not pass through the inner element,

the profile elements of the sash members being located along respective exterior edge portions of the pane in the assembled condition of the sash, and
 the profile elements of the top sash member and the two side sash members being formed as a set of longitudinal profiles of substantially uniform cross-section, wherein each of the longitudinal profiles forming the profile elements of the top sash member and the two side sash

24

members comprises an inner portion adjoining a head portion, said inner portion being configured to overlap the pane in the assembled condition of the sash, and a transition portion is provided between the head portion and the inner portion, said transition portion being configured to accommodate a ridge portion of the intermediate element,

wherein the longitudinal profiles form mitred joints between the profile element of the top sash member and the respective profile element of the side sash members in the assembled condition of the sash, and

wherein a corner key is provided at each mitred joint and wherein the corner key has a generally L-shaped configuration with two perpendicular legs divided by a channel.

7. The roof window according to claim 6, wherein the corner key is supplemented by the application of a sealant, and wherein the channel is provided with a set of primary openings, wherein each leg is adjoined by a depending skirt on a first side, the depending skirt is provided with one or more secondary openings.

8. The roof window according to claim 7, wherein each leg is adjoined by an inclined section on a second side, the channel ending in a tongue adjoining an inclined channel section.

9. The roof window according to claim 6, wherein each profile element comprises a head portion and an adjoining outer portion, wherein the head portion is substantially parallel to the plane of the roof window in the assembled condition of the roof window, and wherein the adjoining outer portion is substantially perpendicular to the head portion.

10. The roof window according to claim 6, wherein the pane comprises an exterior sheet and at least one interior sheet, and wherein the exterior sheet comprises an extended portion extending beyond a bottom edge portion of the at least one interior sheet to a bottom edge portion of the exterior sheet, the pane having a common side edge portion and a common top edge portion.

11. The roof window according to claim 10, wherein a head portion of the profile element of each of the top sash member and the two side sash members is located on an exterior side of the exterior pane surface on an outer side of the common side edge portion and the common top edge portion of the pane, the head portion of the profile element of the bottom sash member being located on an interior side of the extended portion of the exterior sheet of the pane.

12. The roof window according to claim 10, wherein the length of the profile elements of the two side sash members substantially corresponds to or exceeds slightly the distance between the top edge portion of the pane and the bottom edge portion of the exterior sheet of the pane, such that an overlap is provided between the profile elements of the two side sash members and the profile element of the bottom sash member, the inner elements of the sash members forming a coherent inner element sash structure supporting an interior edge portion of the pane in the assembled condition of the sash, the inner elements of the sash members having a substantially identical cross-section.

13. The roof window according to claim 6, wherein the head portion of each profile element is configured to protrude to the exterior relative to an exterior surface of the pane in the assembled condition of the sash.

14. The roof window according to claim 13, wherein the inner portion is inclined from the head portion relative to the

25

head portion and extends inwards and to the interior, towards the exterior surface of the pane in the assembled condition of the sash.

15. The roof window according to claim **14**, wherein the inner portion is adjoined by a first bend configured to be located at or near the exterior surface of the pane, a second bend is provided, said second bend being configured to accommodate a sealing profile relative to the exterior surface of the pane, a third bend is provided, said third bend being configured to accommodate an inner edge portion of the intermediate element relative to an interior side of the inner portion. ¹⁰

16. The roof window according to claim **15**, wherein a fourth bend is provided adjacent the outer portion of the profile element, said fourth bend being configured to accommodate an outer edge portion of the intermediate element. ¹⁵

17. The roof window according to claim **14**, wherein the inner portion of the profile element is configured to be located opposite an inner inclined portion of the intermediate element in the assembled condition of the sash. ²⁰

18. The roof window according to claim **17**, wherein the outer edge portion of the intermediate element is associated with the head portion of the intermediate element via an outer inclined portion and a bend.

19. The roof window according to claim **6**, wherein an outer portion of the profile element of the bottom sash member is configured to be positioned at or near a bottom edge portion of the exterior sheet of the pane. ²⁵

20. The roof window according to claim **19**, wherein a head portion of the profile element of the bottom sash member is provided with at least one longitudinally extending groove configured to receive a sealing profile. ³⁰

21. A roof window comprising a frame, a sash, and a pane, in which the frame comprises a set of frame members including a top frame member, two side frame members and a bottom frame member and the sash comprises a set of sash members including a top sash member, two side ³⁵

26

sash members and a bottom sash member, each frame and sash member defining a longitudinal direction, and the pane comprises a number of edge portions and an exterior pane surface defining a plane of the roof window in an assembled condition of the roof window, each sash member comprising a profile element, an inner element and an intermediate element forming a connection between the profile element and the inner element of each sash member in an assembled condition of the sash, wherein a lowermost portion of the intermediate element is disposed below a lowermost portion of the profile element in the assembled condition of the sash,

the profile elements of the sash members being located along respective exterior edge portions of the pane in the assembled condition of the sash, and

the profile elements of the top sash member and the two side sash members being formed as a set of longitudinal profiles of substantially uniform cross-section, wherein each of the longitudinal profiles forming the profile elements of the top sash member and the two side sash members comprises an inner portion adjoining a head portion, said inner portion being configured to overlap the pane in the assembled condition of the sash, and a transition portion is provided between the head portion and the inner portion, said transition portion being configured to accommodate a ridge portion of the intermediate element,

wherein the longitudinal profiles form mitred joints between the profile element of the top sash member and the respective profile element of the side sash members in the assembled condition of the sash, and

wherein a corner key is provided at each mitred joint and wherein the corner key has a generally L-shaped configuration with two perpendicular legs divided by a channel.
